UNITED STATES PATENT OFFICE.

WILLARD I. LEWIS, OF WALPOLE, MASSACHUSETTS.

DEVICE FOR OPENING AND GUIDING WEBS OF CLOTH, &c.

1,346,549.

Specification of Letters Patent.

Patented July 13, 1920.

Application filed April 12, 1916. Serial No. 90,759.

To all whom it may concern:

Be it known that J. WILLARD I. LEWIS, a citizen of the United States, residing at Walpole, in the county of Norfolk, State of Massachusetts, have invented a certain new and useful Improvement in Devices for Opening and Guiding Webs of Cloth, &c., of which the following is a specification, reference being had therein to the accompanying drawings.

The invention has relation, generally, to devices or machinery for handling traveling continuous webs of cloth and other material. It comprises novel devices applicable for opening or spreading widthwise a web of cloth or the like, straightening out wrinkles and the like, opening-out curled-over selvages, and automatically guiding the web. Devices embodying the invention are adapted to be employed for opening out and spreading widthwise a web of cloth from the so-called rope-form which it sometimes is caused to assume in bleaching and other continuous processes, and for guiding it into certain of the machines by which it is operated upon further. They are fitted to perform the functions of a scutcher in connection with light and delicate goods which would be injured by the reels, beaters, etc., of scutchers constituted as usual in practice.

The invention utilizes the principle or law that a traveling flexible band or the like in moving toward a revolving pulley or roll, the surface of which it envelops partially, tends to travel in a direction at right-angles to the axis of revolution of such pulley or roll. Further, it utilizes the said principle to effect the opening or spreading of a web widthwise, through the employment of obliquely-disposed rolls engaging with both surfaces of an extremely narrow marginal portion of the web, at one or each of the edges of the latter. General objects of the invention are to bring such principle effectively into play in accomplishing the special results to which reference has been made.

The invention consists first in apparatus for opening and spreading a traveling web comprising, in combination web-contracting means by which the web is positively held narrowed widthwise within substantially less than its normal breadth, a roll or set of rolls revolving upon a forwardly-inclined

axis or axes and operating to open and spread the web from its abnormally narrowed state to its full width. By reason of the principle aforesaid, a web-margin extending obliquely outward from the corresponding lateral draft-guiding surface of the web-contracting means to the roll or rolls which engage with such margin tends to work outward along the roll or rolls into a line extending from the said lateral guide-surface to the roll or rolls, at right-angles to the axis or axes of the latter. Usually, in carrying the invention into effect, rolls are employed in conjunction with both of the margins or selvages of a traveling web. By utilizing the said principle in connection with both margins of a web the latter is opened and spread widthwise in both directions from the middle toward both margins, and all wrinkles are straightened out from one margin to the other. The action at one margin opposes that at the other, so that through the balancing of the lateral pull in opposite directions the web is maintained in a middle path.

The invention consists secondly in rolls which are arranged to engage with narrow extreme marginal portions or selvages, only, of the traveling web. More especially it comprises rolls, thus arranged, which are adapted to accommodate themselves to all shifts, outward and inward that happen of the respective margins or selvages due to swaying of the web widthwise, so as to maintain such engagement in all of the different positions of the web transversely. Under this phase of the invention, the rolls for a given margin or selvage comprise one or more that are arranged to make contact with one surface of the web, and one or more that are arranged to make contact with the other surface thereof. Usually, more than two rolls are employed in a group. In order that the web may be held only by narrow marginal portions thereof, the rolls of one set of a group are alternated with those of the other set of such group, and in addition the axes of the rolls of one set are inclined in the direction of their length with respect to those of the coöoperating set so that in the different working positions of the two sets of rolls the two planes containing the axes of the respective sets intersect and cross each other. The web-margin is entered into the inner

angle between the two sets of rolls. In order that the rolls may accommodate themselves to lateral swaying of the web-margin, they are mounted in carriers which are adapted to swing so as to permit the two sets of rolls to open as the margin shifts farther outward in between the two sets of rolls, and the said roll-carriers are actuated with yielding force to close the rolls upon the margin as it shifts inward and withdraws partially from between the two sets, toward the inner ends of the rolls. In other words, the two sets of rolls are mounted and arranged so that the place of crossing of the two sets shifts outward and inward as the position of the web-margin changes.

In the drawings,—

Figure 1 is a view in side elevation of certain cloth-handling apparatus having an embodiment of the invention applied thereto.

Fig. 2 is a front elevation of the opening, spreading, etc., devices of Fig. 1, the web being omitted.

Fig. 3 is a plan view of the parts of Fig. 2.

Fig. 4 is a detail view of the adjusting means hereinafter described.

Having reference to the drawings, and first to Fig. 1,—

From any convenient source, which in some cases will be a suitable container, for instance a truck holding a considerable quantity of cloth in continuous web-form, the web 1 passes to and partly around an overhead guide-roll 3, around which it changes direction and passes to and partly around a feed-roll 4 having a frictional surface for engagement with the web. The two rolls 3 and 4 are mounted in any convenient supports (not shown). Feed-roll 4 is rotated by suitable power-connections, and through its rotation and the engagement of its surface with the web it draws the latter from the source of supply to facilitate its passage to and through the devices involved in the invention, which are arranged in position to act upon the web on its way from the said feed-roll 4. One or more rotating scutcher-reels, as 2, may be employed to act upon the web in advance of its arrival at rolls 3, 4, so as to effect a preliminary loosening-up and opening of the web. From roll 4 the web passes down to and partly around a guide-roll 3^a, suitably supported in position from which it passes horizontally to the said devices. A pair of feed-rolls 5, 6, engaging with the web after it has passed the said devices, operates to draw the web forward past and away from the latter and advance it to the cloth-handling apparatus by which the web is next to be operated upon, the devices in question operating to cause the web to arrive at the said ap-

paratus in a flat open state, laterally expanded and free from wrinkles, with its margins traveling along predetermined lines. The journals 7 of feed-roll 5 are mounted in bearings (not shown) carried by the fixed frame-work. Those of feed-roll 6 are mounted in bearings provided in connection with arms 9 fixed upon a supporting rock-shaft 10 that is mounted in bearings (not shown) in connection with the fixed framework, the said rockshaft having an arm 11 carrying a weight 12 acting with a tendency to rock the rockshaft and press the feed-roll 6 toward feed-roll 5. The web arriving at these feed-rolls passes under and partly around feed-roll 6, then between the latter and feed-roll 5, and from feed-roll 5 to the succeeding cloth-handling apparatus. The particular parts thus far referred to are illustrative merely, and their construction, etc., is not involved in the invention.

The means for keeping the margins of the web contracted within less than the normal breadth of the web, so that in passing onward from the said means the latter shall diverge widthwise of the web to the rolls for opening and spreading the web and guiding it in the required path, may be of any suitable form and arrangement which will be suggested to those skilled in the art. Herein the means in question comprises an ordinary large pot-eye 13 located at a convenient distance from the opening and spreading and guiding devices, and carried by a rail 14 which is supported by a part of the framework. In this instance, the web in rope-form passes through the pot-eye 13. Opposite portions of the interior surface of the pot-eye constitute guides for the opposite margins of the web, and serve to confine such margins within less than the normal width of the web. Such portions constitute fixed lateral guide-surfaces serving as draft-guides from which the web-margins or selvages, respectively, extend outward in oblique directions to the rolls for opening and spreading the web widthwise, etc. When the web to be operated upon is already in a more or less opened and spread-out state, other means of confining the web widthwise within substantially less than its normal breadth, and providing lateral draft-guides may be employed in practice.

The rolls are shown in place in the apparatus in Fig. 1, and are shown separately on a larger scale in Figs. 2 and 3. They comprise in this instance two groups B, C, of transversely-extending rolls of small diameter, there being one group for each margin of the web. The number of rolls comprised in the respective groups may vary in practice. Figs. 1 and 3 show the inclination of the axes of the rolls of the different groups forwardly in the direction of travel of the

web. It is in consequence of this inclination that, as the web advances, the revolution of the rolls tends to expand the web transversely, in conformity with the principle referred to at the outset herein. As stated above, the rolls of each group are divided into two sets, one thereof comprising those marked 15, 15, etc., and making contact with one face of the web-margin, and the other comprising those marked 16, 16, etc., and making contact with the other face of the said web-margin. The two sets of rolls of a group are supported separately by roll-carriers 17, 17, and the said roll-carriers have capacity for relative movement to permit of such an opening or separation of the two sets of rolls with relation to each other as will allow a web-margin to be entered between the two sets, and to permit of such a closing of the two sets together as will cause the respective sets to engage with opposite surfaces of the web-margin thus entered between them. The two sets of rolls are caused to tend to close together upon the said web-margin by the tension of actuating springs acting upon the roll-carriers, as explained later herein.

The preferred construction providing for the support of the two sets of rolls of each group, and for the relative movement of the said sets, is as follows:—The rolls of one set are journaled upon one roll-carrier 17, and those of the other set are journaled upon a similar roll-carrier. Herein, each of the roll-carriers is furnished at its opposite ends with outwardly-extending ears or lugs 18, 18, which fit upon and are made fast to a shaft 19 located alongside the path of the web and in a plane parallel with the plane of the latter. There are two shafts 19, 19, one for each roll-carrier. The two shafts 19, 19, are parallel with each other, and are mounted in bearings in connection with two pairs of supporting-blocks 20, 20. The supporting-blocks 20, 20, are mounted upon screw-threaded shafts 21, 21, which in turn are mounted in a swing frame 22. The said swing-frame is mounted upon suitable supports in connection with the main frame-work of the apparatus, as explained later herein.

By mounting the two shafts 19, 19, in bearings in connection with the two pairs of supporting-blocks 20, 20, the two roll-carriers 17, 17, are rendered capable of swinging about the axes of the shafts 19, 19, in a plane intersecting at right-angles the plane of the web, in order thereby to provide for the required relative movement of the two sets of rolls. It is not necessary in all cases that both sets of rolls should be adapted to swing.

For the application of the force by which the two sets of rolls of a group are caused to close together upon the web-margin between

them, each roll-carrier 17 is furnished with arms 23, 23, fixed upon the opposite ends of its shaft 19 and extending toward the middle of the width of the apparatus, and contracting spiral springs 24, 24, are provided to act in conjunction with these arms. The tension of these springs, transmitted to the said arms, tends to occasion turning movement of the shafts 19, 19, and thereby produce swinging movement of the roll-carriers 17, 17, so as to effect the closing together of the two sets of rolls. In order that the tension of the springs may be applied to both of the sets of rolls of a group equally, and in order also that when relative movement of the two sets of rolls with respect to each other takes place both sets of rolls may be caused to move simultaneously either toward each other or apart from each other, the two arms 23, 23, at each end of the group of rolls have connected therewith links 25, 25, which converge and have their meeting ends joined by a pin 26 working in a slot 27 in an end-flange 22^a of the swing-frame 22. The said slot is at right-angles with respect to the adjacent screw-threaded shaft 21, and is located about midway between the two shafts 19, 19, and their arms 23, 23. The walls of the slot 27 confine and guide the pin, and restrict it to movement along a line at right-angles to the said screw-threaded shaft. The spring 24 located at such end of the group is engaged with the pin 26, and acts through the latter and the two links 25, 25, to apply force equally to both rockshaft arms 23, 23, so as to produce equal pressure of the two sets of rollers against the opposite surfaces of the web-margin in closing them together upon such margin. It is to be observed that force acting through either or both sets of rolls, tending to rock one or both roll-carriers in opposition to the tension of the springs 24, 24, and transmitted through one or both links at each end of the roll-carrier arrangement to the pin 26, will operate to move such pin in the direction of the length of the slot against the resistance of the spring. By reason of the connection of the pin through the links with both of the roll-carriers, and of the intermediate location of the slot, neither set of rolls can be caused to swing away from the other set without corresponding movement of the latter, so that movement imparted to the one set will be transmitted to the other, and the two sets will be compelled to move simultaneously at the same speed to an equal extent in opposite directions with respect to each other.

As indicated previously herein, engagement of the rolls with narrow extreme marginal portions or selvages, only, of the traveling web is provided for by arranging the rolls of a given group so that those of the set which engage with one surface of the web alternate in succession with those of the

set which engage with the other surface, and with the axes of the two sets of rolls in planes at an inclination with respect to each other so that such planes intersect and cross, and by entering the web-margin into the inner angle between the two sets of rolls. The alternation of the rolls of the two sets is shown in Figs. 1 and 3 of the drawings. In such figures, as preferred, one of the said sets comprises the first, third, and remaining odd-numbered rolls of the group, these being marked 15, 15, etc., while the other set comprises the second, fourth, and remaining even-numbered rolls of the group, these being marked 16, 16, etc. The relative inclination is indicated in Figs. 1 and 2. In Figs. 2 and 3 the two sets of rolls of each group are represented as closed fully under the action of the springs 24, 24, in the absence of the web, so that in such views the inner portions of the two roll-carriers 17, 17, of a group are in immediate contact with each other. When a web is introduced into the apparatus, the inner ends of the two sets of rolls, 15 and 16, of a group are opened or spread apart, which may be done by swinging the roll-carriers oppositely with relation to each other around the axes of the shafts 19, 19, so as to separate the contacting inner portions of the roll-carriers from each other, and the corresponding web-margin is inserted between the inner ends of the two sets of rolls, at the inner side of the place of crossing of the two sets. Then the roll-carriers are freed to the action of the springs 24, 24, which thereupon operate the roll-carriers to close the two sets of rolls together upon the web-margin, as, now, the web is drawn onward through the apparatus, the engagement of the surfaces of its margins with the rolls of the two groups will revolve the rolls upon their individual axes, and by reason of the principle already referred to each margin will work outwardly along the rolls of the corresponding group until the tendency of either web-margin to move outward in one direction is counterbalanced by the like tendency of the opposite web-margin to move outward in the other direction. The web will then continue to move onward in the path thereby established varying therefrom only slightly as different causes may produce lateral swaying of the web and returning at once to such path.

By reason of the employment of web-contracting means by which the web is positively held narrowed widthwise within substantially less than its normal breadth in advance of the rolls, and by reason of the fact that the opening and spreading rolls take hold of the web only by its extreme edge-portions, the draft that is transmitted along a margin or selvage acts between the point at which the latter is nipped by the

rolls, and the point at which it bends around the lateral guide-surface of the web-contracting means which serves as a draft-guide, to open and unroll or uncurl curled-over selvages.

By reason of the tendency of the two sets of rolls of a group to close together upon the corresponding web-margin, the contact of rolls of either set with the web-margin at points opposite the spaces of the other set 75 operates to bend the web more or less between and partly around the successive rolls, and to produce frictional engagement between the peripheries of the rolls and the web-margins sufficient for the purposes of 80 the invention. The force which produces the tendency to close the two sets of rolls upon the web acts yieldingly, and in practice is proportioned so as not to create too strong a pressure of the rolls upon the web. 85 Preferably, a considerable number of rolls is employed in each group, to divide up the pressure and reduce the extent to which the web is bent in between the successive rolls of the two sets.

The angle of relative inclination of the two sets of rolls of a group may be varied, as may be found advisable for securing the best results in practice, by moving the two roll-carrier supporting shafts 19, 19, of such 95 group closer together or farther apart, as the case may require. To this end, each screw-threaded shaft 21 is furnished with a right-hand thread on the portion thereof on which one bearing-block 20 is mounted, 100 and with a left-hand thread on the portion thereof on which the adjacent bearing-block 20 is mounted. When the shafts 21, 21, are rotated by means of the crank-handles with which they are shown furnished (or by 105 other suitable devices) the desired adjustment of shafts 19, 19, and consequently of the inclination of the roll-carriers and rolls, will be effected.

Provision is made for adjustment of the 110 forward inclination of the axes of the rolls of each group, and thereby of the angle of divergence of the two groups of rolls, by employing the swing-frame 22 as a support for the roll-carriers 17, 17, of a group of 115 rolls 15, 16, and by providing means for varying the angular position of the said swing-frame and the said rolls in a plane parallel with that of the web passing through the roll-system. In this embodiment of the invention, each swing-frame 22 is mounted pivotally, as at 22°, upon a support 30, and is engaged at the point 31 with a collar 32 mounted loosely upon a cross-rod 33, which latter extends at its ends through 125 slots 34, 34, in opposite portions 35, 35, of the fixed framework of the apparatus. Bodily shift of rod 33 within slots 34, 34, serves through collars 32, 32, and their engagement with the two swing-frames 22, 22, to swing 130

the latter simultaneously around their pivots 22^b, 22^b, thereby altering the forward inclinations of the two groups of rolls, and the angle of the longitudinal axes of the 5 rolls of one group with respect to those of the rolls of the other group. This bodily shift of the rod 33 may be effected in various ways in practice. Herein it is provided for by adjustment-devices by means of which 10 both ends of the rod may be adjusted simultaneously. The said adjustment-devices comprise toggle-arrangements which are duplicated at the opposite sides of the apparatus, and means whereby said toggle-arrangements 15 may be bent in unison more or less. The toggle-arrangement at each end consists of two links 36, 37, the first of which is engaged by the outer end thereof with one end of rod 33, while the other is engaged by the outer end thereof with one end 20 of a cross-rod 38 mounted in the portions 35, 35, of the framework, and the meeting ends of the two links are engaged with a nut 39 upon a screw-threaded shaft 40 mounted in 25 a fixed bearing-support 41. Such engagement is provided for in the present instance, as shown in Fig. 4, by causing the projecting end of the pivot 36^a, which connects said meeting ends together, to occupy a slot 30 or groove 39^a in the inner side of said nut 39. The said slot or groove is of sufficient length to allow the pivot-pin freedom for the extent of forward and rearward movement thereof which is incident to the bending 35 of the toggle in effecting adjustments. By turning the screw-threaded shaft 40 so as to screw the nut 39 up or down the toggle is actuated so as to shift the rod 33. For the purpose of enabling the two screw-threaded shafts 40, 40, to be turned in unison from either side of the apparatus, each 40 thereof is furnished with a bevel-gear 42, and the respective bevel-gears 42, 42, are engaged by bevel-gears 43, 43, fixed upon 45 opposite ends of a cross-shaft 44 mounted in bearings in the bearing-supports 41, 41, and provided with hand-wheels 45, 45, that are fixed upon the said opposite ends.

Adjustment of the two groups of rolls toward and from each other widthwise of the 50 apparatus, to suit different widths of webs, is provided for by making the supports 30, 30, correspondingly adjustable, and furnishing convenient adjustment means in connection therewith. For the purposes of the 55 adjustment, the supports 30, 30 are mounted upon the cross-rod 38 and a cross-shaft 46 that is disposed parallel therewith, by means of lugs fitting said cross-rod and cross-shaft 60 with capacity to slide along such rod and shaft in the direction of the width of the apparatus, and the cross-shaft 46 is furnished with right-hand and left-hand screw-threads upon its opposite end-positions, upon 65 which are fitted nuts 47, 47, engaged in

pockets formed in certain of the lugs with which the supports 30, 30, are formed. By taking hold of either of the crank-handles 48, 48, which are fixed upon opposite ends of the screw-threaded adjustment-shaft 46, 70 and rotating the said shaft, the supports 30, 30, and respective groups of rolls may be moved closer together or farther apart, to suit the width of the web to be operated upon. 75

I claim as my invention:—

1. Apparatus for opening and spreading a traveling web, comprising, in combination, web-contracting means by which the web is positively held narrowed widthwise within substantially less than its normal breadth, a roll or set of rolls to which a web-margin extends obliquely outward from said web-contracting means, said roll or set of rolls revolving upon a forwardly-inclined axis or 80 axes and operating to open and spread the web from its abnormally narrow state to its full width and means for producing engagement between the roll or rolls and the web. 85

2. Apparatus for opening and spreading a traveling web, comprising, in combination, web-contracting means by which the web is positively held narrowed widthwise within substantially less than its normal breadth, a roll or set of rolls at each side of the path 90 of the traveling web after it leaves the said means, to which the web-margins extend obliquely outward from said web-contracting means, said roll or rolls respectively revolving upon a forwardly-inclined axis or 95 axes, and operating by their joint action to open and expand such web transversely from its abnormally narrowed state to its full width and means for producing engagement between the roll or rolls and the web. 100 105

3. Apparatus for opening and spreading a traveling web, comprising, in combination, web-contracting means by which the web is positively held narrowed widthwise within substantially less than its normal breadth, a roll or set of rolls to which a web-margin extends obliquely outward from said web-contracting means, said roll or set of rolls revolving upon a forwardly-inclined axis or 110 axes, arranged to engage with a narrow extreme marginal portion or selvage, only, of the traveling web, and tending to open and spread said web transversely from its abnormally narrowed state to its full width and means for producing engagement between the roll or rolls and the web. 115 120

4. Apparatus for opening and spreading a traveling web, comprising, in combination, web-contracting means by which the web is positively held narrowed widthwise within 125 substantially less than its normal breadth, a roll or set of rolls at each side of the path of the traveling web to which the web-margins extend obliquely outward from said web-contracting means, said roll or rolls re- 130

volving upon a forwardly-inclined axis or axes, the roll or rolls at each side, respectively, arranged to engage with a narrow extreme portion or selvage, only, of the said traveling-web, and the opposite rolls or sets of rolls tending by their joint action to open and spread such web transversely from its abnormally narrowed state to its full width and means for producing engagement between the roll or rolls and the web.

5. Apparatus for opening and spreading a traveling web, comprising, in combination, web-contracting means by which the web is held narrowed widthwise within substantially less than its normal breadth, a roll or set of rolls revolving upon a forwardly-inclined axis or axes, to which a web-margin extends obliquely outward from said web-contracting means, said roll or set of rolls arranged to engage by a narrow fraction, only, of the portion of the length thereof which extends inward of the edge of the web with a narrow extreme marginal portion or selvage of the web, and tending to open and spread said web transversely from its abnormally narrowed state to its full width and means for producing engagement between the roll or rolls and the web.

6. Apparatus for opening and spreading a traveling web, comprising, in combination, web-contracting means by which the web is held narrowed widthwise within substantially less than its normal breadth, a roll or set of rolls at each side of the path of the web, to which the web-margins extend obliquely outward from said web-contracting means, said roll or rolls revolving upon a forwardly-inclined axis or axes, the roll or rolls at each side respectively arranged to engage by a narrow fraction, only, of the portion of the length thereof which extends inward of the edge of the web with a narrow extreme marginal portion or selvage of the web, and tending by their joint action to open and spread such web transversely from its abnormally narrowed state to its full width and means for producing engagement between the roll or rolls and the web.

7. Apparatus for opening and spreading a traveling web, comprising, in combination, web-contracting means by which the web is held narrowed widthwise within substantially less than its normal breadth, a roll or set of rolls revolving upon a forwardly-inclined axis or axes, to which a web-margin extends obliquely outward from said web-contracting means, said roll or set of rolls arranged to engage by a narrow fraction, only, of the portion of the length thereof which extends inward of the edge of the web with a narrow extreme marginal portion or selvage of the web, and tending to open and spread said web transversely from its abnor-

mally narrowed state to its full width and means for producing engagement between the roll or rolls and the web.

8. Apparatus for opening and spreading a traveling web, comprising, in combination, web-contracting means by which the web is held narrowed widthwise within substantially less than its normal breadth, a roll or set of rolls at each side of the path of the web, to which the web-margins extend obliquely outward from said web-contracting means, said roll or rolls revolving upon a forwardly-inclined axis or axes, the roll or rolls at each side respectively arranged to engage by a narrow fraction, only of the portion of the length thereof which extends inward of the edge of the web with a narrow extreme marginal portion or selvage of the web in all shifts outward and inward of the margin or selvage as the web travels past, and tending by their joint action to open and spread the web transversely from its abnormally narrowed state to its full width and means for producing engagement between the roll or rolls and the web.

9. In a web-handling apparatus, in combination, a group of rolls revolving upon forwardly-inclined axes and comprising one or more rolls arranged to engage with one surface of a margin or selvage of a traveling web, and one or more arranged to engage with the other surface thereof, with the axes of the rolls engaging with the respective surfaces of the margin or selvage arranged to have working positions in planes transversely inclined to each other so that the surfaces of said rolls shall engage with a narrow extreme edge-portion, only, of the interposed margin or selvage and means for causing travel of the web in engagement with the various rolls.

10. In a web-handling apparatus, in combination, opposite groups of rolls revolving upon forwardly inclined axes and adapted to coöperate with opposite margins or selvages of a traveling web, the respective groups converging forwardly, and each group comprising a roll or rolls arranged to engage with one surface of the corresponding margin or selvage and a roll or rolls arranged to engage with the other surface thereof, with the axes of the rolls engaging with the respective surfaces of a margin or selvage arranged to have working positions in planes transversely inclined to each other so that the surfaces of said rolls shall engage with a narrow portion only of the interposed margin or selvage and means for causing travel of the web in engagement with the various rolls.

11. In a web-handling apparatus, in combination, a web-guide by which the margin or selvage of a traveling web is guided, and a group of rolls to which the said margin or selvage proceeds from the said web-guide,

- the said rolls revolving upon forwardly-inclined axes and the group comprising one or more rolls arranged to engage with one surface of the margin or selvage, and a roll or 5 rolls arranged to engage with the other surface thereof, with the axes of the rolls engaging with the respective surfaces of the margin or selvage arranged to have working positions in planes transversely inclined to each other so that the surfaces of said rolls shall engage with a narrow edge-portion only of the interposed margin or selvage and means for causing travel of the web in engagement with the various rolls. 10
12. In a web-handling apparatus, in combination, guiding means by which the margins or selvages of a traveling web are guided, and opposite groups of rolls to which the said margins or selvages proceed 15 from the said guiding means, the respective groups converging forwardly and each group comprising a roll or rolls arranged to engage with one surface of the corresponding margin or selvage and a roll or rolls arranged to engage with the other surface thereof, with the axes of the rolls engaging with the respective surfaces of a margin or selvage arranged to have working positions in planes transversely inclined to each other so that the surfaces of said rolls shall engage with a narrow edge-portion only of the interposed margin or selvage, and means for causing travel of the web in engagement with the various rolls. 20
13. In a web-handling apparatus, in combination, a web-guide by which the margin or selvage of a traveling web is guided, and a group of rolls to which the said margin or selvage proceeds from the said web-guide, the said rolls revolving upon forwardly-inclined axes, and the group comprising one or more rolls arranged to engage with one surface of the said margin or selvage and one or more arranged to engage with the other surface thereof, with the axes of the rolls that engage with the respective surfaces of the margin or selvage arranged to have working positions in planes transversely inclined to each other so that the surfaces of the said rolls shall engage with a narrow edge-portion only of the interposed margin or selvage, and means for closing the rolls yieldingly together against the opposite surfaces of the interposed margin or selvage. 25
14. In a web-handling apparatus, in combination, guiding means by which the margins or selvages of a traveling web are guided, and opposite groups of rolls to which the said margins or selvages proceed 30 from the said guiding means, the respective groups converging forwardly and each group comprising a roll or rolls arranged to engage with one surface of the corresponding margin or selvage and a roll or rolls arranged to engage with the other surface thereof, with the axes of the rolls that engage with the respective surfaces of the margin or selvage arranged to have working positions in planes transversely inclined to each other so that the surfaces of the said rolls shall engage with a narrow edge-portion only of the interposed margin or selvage, and means for closing the rolls yieldingly together against the opposite surfaces of the interposed margin or selvage. 35
15. In a web-handling apparatus, in combination, a web-guide by which the margin or selvage of a traveling web is guided, and a group of rolls to which the said margin or selvage proceeds from the said web-guide, the said rolls revolving upon forwardly-inclined axes and the group comprising a set of rolls arranged to engage with one surface of the said margin or selvage and a set of rolls arranged to engage with the other surface thereof, with the rolls of one set alternated with those of the other set, and with the axes of the rolls of the respective sets arranged to have working positions in planes transversely inclined to each other so that the two sets shall at any one time engage with a narrow edge-portion only of the interposed margin or selvage. 40
16. In a web-handling apparatus, in combination, a web-guide by which the margin or selvage of a traveling web is guided, and a group of rolls to which the said margin or selvage proceeds from the said web-guide, the said rolls revolving upon forwardly-inclined axes and the group comprising a set of rolls arranged to engage with one surface of the said margin or selvage and a set of rolls arranged to engage with the other surface thereof, with the rolls of one set alternated with those of the other set, and with the axes of the rolls of the respective sets arranged to have working positions in planes transversely inclined to each other so that the two sets shall engage with a narrow edge-portion only of the interposed margin or selvage, and means for closing the two sets of rolls yieldingly together against the opposite surfaces of the margin or selvage. 45
17. In a web-handling apparatus, in combination, guiding means by which the margins or selvages of a traveling web are guided, and opposite groups of rolls to which the said margins or selvages proceed from the said guiding means, the respective groups converging forwardly and each group comprising a set of rolls arranged to engage with one surface of the corresponding margin or selvage and a set of rolls arranged to engage with the other surface thereof, with the rolls of one set alternated with those of the other set, and with the axes of the rolls of the respective sets arranged to have working positions in planes transversely inclined to each other so that the two sets shall engage with a narrow edge-portion only of the interposed margin or selvage, and means for closing the two sets of rolls yieldingly together against the opposite surfaces of the margin or selvage. 50

versely inclined to each other so that the two sets shall engage with a narrow edge-portion only of the interposed margin or selvage.

5 18. In a web-handling apparatus, in combination, guiding means by which the margins or selvages of a traveling web are guided, and opposite groups of rolls to which the said margins or selvages proceed from 10 the said guiding means, the respective groups converging forwardly and each group comprising a set of rolls arranged to engage with one surface of the said margin or selvage and a set of rolls arranged to 15 engage with the other surface thereof, with the rolls of one set alternated with those

of the other set, and with the axes of the rolls of the respective sets arranged to have working positions in planes transversely inclined to each other so that the two sets shall 20 engage with a narrow edge-portion only of the interposed margin or selvage, and means for closing the two sets of rolls yieldingly together against the opposite surfaces of the interposed margin or selvage. 25

In testimony whereof I affix my signature in presence of two witnesses.

WILLARD I. LEWIS.
